COMBINED ROASTING RACK AND SKEWER

Walter H. Krause, Chicago, Ill., assignor to Beacon
Metal Products Company, Chicago, Ill., a partnership

Application April 10, 1957, Serial No. 45,663

Term of patent 3½ years

(Cl. D81—10)

Fig. 1

Figure 1 is a perspective view of a combined roasting rack and skewer embodying my new design;
 I claim:

The ornamental design for a combined roasting rack and skewer, as shown.
